United States Patent Office

Des. 210,793
Patented Apr. 16, 1968

210,793

ORBITAL SANDER

Harvey B. Rodstein, 6419 Shenandoah,
Los Angeles, Calif. 90056

Filed Sept. 20, 1967, Ser. No. 8,664

Term of patent 3½ years

(Cl. D37—1)

FIGURE 1 is a plan view of the orbital sander showing my new design;

FIGURE 2 is a side elevational view thereof;

FIGURE 3 is a front elevational view;

FIGURE 4 is a rear view thereof.

I claim:

The ornamental design for an orbital sander, substantially as shown and described.
